UNITED STATES PATENT OFFICE.

JOAQUIN MIRANDA AMADOR, OF HABANA, CUBA.

CARBURETOR.

Application filed June 4, 1926. Serial No. 113,780.

This invention relates generally to carburetors used on internal combustion engines, the invention having more particular reference to a novel type of carburetor.

5 The invention has for an object the provision of a carburetor embodying certain adjustable and variable elements.

For further comprehension of the invention, and of the objects and advantages 10 thereof, reference will be had to the following description and accompanying drawing, and to the appended claim in which the various novel features of the invention are more particularly set forth.

15 Fig. 1, of the drawings, is a front elevational view of my improved carburetor.

Fig. 2, is a rear elevational view thereof.

Fig. 3, is a top plan view thereof.

20 Fig. 4, is a bottom plan view of the mixing chamber, as seen from the line 4—4 of Fig. 2.

Fig. 5, is a longitudinal vertical central sectional view of my improved carburetor.

25 Fig. 6, is a transverse sectional view, taken on the line 6—6 of Fig. 2.

Fig. 7, is a longitudinal vertical central sectional view, illustrating a modification of my improved carburetor.

30 Fig. 8 is a top plan view thereof.

Fig. 9, is an enlarged view of the air inlet valve shown in Fig. 7.

As here embodied my improved carburetor for internal combustion motors comprises an air intake member 10, of hollow construction, and is provided with a butterfly valve 11 having a lever 12, to regulate or control the air entering the mixing chamber of the carburetor, the valve 11 being of the type commonly used in carburetors for internal combustion motors.

40 The mixing chamber 13, has a lower depending flange 14, adapted to receive the air intake member 10, which is removably attached thereto by screws 15, studs, bolts, or the like. The mixing chamber 13 is provided with two separate lower chambers 16, oppositely positioned therein, and separated by a lower central wall 17. The two lower chambers 16 are connected with the upper chamber 16'. The butterfly valves 18 and 19 are pivoted, as at 20, in the mixing chamber 13, and are positioned in the two lower separate chambers 16, so as to regulate or control the air entering the upper chamber 21, from the said mixing chamber. The lever 22, is attached, as at 23 to the butterfly valve 19,

and is pivotally connected to the bell crank 24, by the rod 25. The bell crank 24 being suitably connected, at its extremity 26, by any suitable controlling device, rods, flexible 60 members or the like not shown in the drawings, to any suitable and conveniently located throttle, of the type commonly used to regulate or control butterfly valves of carburetors of the class described.

65 The needle valve 27 is slidably positioned in a suitable aperture 28 located in the said central wall 17, located outside the two separate chambers 16, and adjacent thereto, and extends downward, and through an aperture 29, located in the jet 30, which is threadedly attached to the central wall 17. It should be understood that the needle valve 27 is provided with a pointed extremity 31. The above described construction is such as 70 75 will permit the needle valve 27 when raised and lowered to permit a greater or lesser amount of fuel to enter the orifice 32 communicating with the center aperture 33 of the central wall 17. It should also be understood that the orifice 34 is located below 80 the said jet 30, and is in communication with the said center aperture 33.

85 A plug 35 is threadedly attached to the center aperture 33, and is provided with an axial aperture 36. The aperture 37 is located in the central wall 17, and is connected with the aperture 33 and with the upper chamber 16'. The plug 38 is threadedly attached to the lower portion of the aperture 33.

90 The mixing chamber 13 is provided with a flange 39 located at the upper extremity thereof, and is adapted to receive a similar flange of an intake manifold of an internal combustion motor not shown in the drawing.

95 The above described device is such as will permit the fuel, gasoline, kerosene, or the like when the above referred to internal combustion motor is set in operation, to be drawn 100 or sucked through the orifice 34, through the axial aperture 36 of the plug 35, through the aperture 37, through the upper chamber 16' and into the combustion chamber of the said internal combustion motor, when the 105 said needle valve 27 is in a closed position. It should be understood that the said axial aperture 36 of the plug 35 will be of sufficient size or diameter, to permit the said internal combustion motor to run at only a 110 low, or idling speed. The plug 35 may be removed or replaced by a similar plug not

shown in the drawings having a smaller or larger passage therethrough as desired for the purpose of suitably adjusting the permanent flow of liquid for regulating the idling 5 rotation of the motor. The above described construction is such as will also permit the said fuel, when the needle valve 27 is in an opened position, to be drawn or sucked through the aperture 29, through the aperture 33, through the upper chamber 16' and into the combustion chamber of the said internal combustion motor. It should be understood that the threaded lower extremity 40 of the aperture 29 is adapted to receive 10 a suitable connection as a means of connecting thereto a fuel line suitably connected to a fuel tank of the type ordinarily used in connection with internal combustion motors.

The needle valve 27 is provided with an 20 enlarged head 41, positioned over the arm 42, having an aperture 43 adapted to receive the needle valve 27. The arm 42 is pivotally attached, as at 44, to a support 45, attached to the mixing chamber 13, and has pivotally 25 attached thereto, as at 46, a rod 47, pivotally attached to the arm 48, of the above mentioned butterfly valve 18.

The above described construction is such 30 as will permit the above mentioned lever 24 when pivoted, to open the said needle valve 27, any desired amount, so as to permit a greater or smaller quantity of fuel to enter the combustion chamber of the said internal combustion motor.

35 My improved carburetor may also have threadedly attached thereto, an auxiliary air needle valve 49 positioned in the aperture 50. The aperture 50 is connected with the said central aperture 37, and with an aperture 51, so as to permit any desired quantity of air to be sucked into the upper chamber 16', and mixed with the fuel, as may be required for a proper combustible mixture, as is common practice with carburetors of 45 all classes and types.

Referring in particular in Figs. 7, and 8, of the accompanying drawings, in which I have illustrated a modification of my improved carburetor, the float chamber 60 is 50 provided with a cover 61, adapted to contain a float 62, having attached thereto an arm 63, pivoted as at 64, and pivotally attached, as at 65, to the needle valve 66. The needle valve 66 is slidably mounted in the cap 67, 55 suitably attached to the auxiliary chamber 68. An inlet connection 70 is attached by threads shown at 60 to the wall of the auxiliary chamber 68 as a means of attaching the inlet swivel 71 adapted to receive a 60 fitting such as commonly used to connect a fuel line. The fuel line or conduit may be connected to a suitable fuel tank. The tank and fuel conduit are not being shown in the above referred to Figs. 7 and 8 of 65 the accompanying drawings but are of com-

mon ordinary construction and design, such as generally used in carburetors of the class and type described.

The inlet connection 70 is provided with an axial aperture 71, adapted to receive a 70 tubular member 72, provided with radial apertures 73, communicating with radial apertures 74, located in the inlet connection 70. The above described construction is such as will permit the radial apertures 73 of the 75 tubular member 72, to determine the quantity of fuel delivered to the needle valve 66. It should be understood that the number and size or diameter of the said radial apertures 73 will determine the above referred to quantity of fuel; it being further understood that the fuel will take or be sucked through, as hereinbefore set forth, the passages designated by the indicating arrow clearly 80 shown in Fig. 7, and that the outlet 75 will be suitably connected to the combustion chamber of the above referred to internal combustion motor.

The needle valve 57 is attached to the cover 61 by means of a nut 55, having a needle 58, 90 as a means of permitting the outlet of air through the orifice 56. Needle 58 having attached to its lower extremity, a thin rod which is raised by the arm 63 and opens the valve.

Having thus described my invention, what I claim as new and desire to protect by Letters Patent of the United States is as follows:

A carburetor of the class described comprising a casing having an air passage therethrough, a wall in said casing comprising an external extension, said wall and extension being provided with substantially vertical apertures communicatively connected at their upper extremities by a passage through said wall and said extension and communicatively connected intermediate their extremities by a second passage through said wall and extension, a valve seat disposed 100 in the aperture of said extension between the passages communicating therewith, a plug screw threaded in the aperture of said wall for providing a well there above, a plug disposed in the aperture of said wall 105 between the passages therein so as to divide said well into upper and lower chambers, said second-named plug having an orifice 110 therein adapted to permit liquid fuel to flow therethrough from said lower chamber to 115 said upper chamber, a passageway for supplying air to said upper chamber whereby 120 said fuel may be partially emulsified before passing into the air passage of the casing, means for regulating the amount of air flowing 125 through said passageway, and a second passage from said upper chamber into the air passage of said casing for producing a mixture of air and fuel of predetermined 130 richness, and a needle valve disposed through 135

an aperture in said extension engaged with said valve seat at its lower end and extending above said extension at its upper end adapted to be manually manipulated during 5 operation of said carburetor for permitting liquid fuel to pass through said valve seat and through the uppermost passage in said wall and extension into the aperture of said

wall to unite with the liquid fuel discharged through the orifice of said second-named 10 plug for suitably increasing the richness of the mixture of air and fuel in said air passage above a predetermined amount.

In testimony whereof I have affixed my signature.

JOAQUIN MIRANDA AMADOR.
